UNITED STATES PATENT OFFICE

157,110

LUNCH BOX

Lawrence Welk, River Forest, Ill.

Application January 17, 1949, Serial No. 272

Term of patent 14 years

(Cl. D58—12.6)

To all whom it may concern:

Be it known that I, Lawrence Welk, a citizen of the United States, residing at River Forest, in the county of Cook and State of Illinois, have invented a new, original, and ornamental Design for a Lunch Box, of which the following is a specification, reference being had to the accompanying drawing, forming part thereof.

I claim:

The ornamental design for a lunch box, as shown.

LAWRENCE WELK.
